UNITED STATES PATENT OFFICE.

JOHN H. HUNT, OF DAYTON, OHIO, ASSIGNEE TO THE DAYTON ENGINEERING COMPANY, A CORPORATION OF OHIO.

IGNITION SYSTEM.

Application filed January 2, 1918. Serial No. 209,844.

To all whom it may concern:

Be it known that I, JOHN H. HUNT, a citizen of the United States of America, residing at Dayton, county of Montgomery, and State of Ohio, have invented certain new and useful Improvements in Ignition Systems, of which the following is a full, clear, and exact description.

This invention relates to ignition equipment for multi-cylinder engines and has for its object the provision of means for preventing ignition upon reversal of the engine.

Further objects and advantages of the present invention will be apparent from the following description, reference being had to the accompanying drawings, wherein a preferred embodiment of the present invention is clearly shown.

Fig. 1 is an end view of a V-type engine having an overhead cam shaft enclosed in a housing upon the ends of which are mounted ignition units embodying the present invention;

Fig. 2 is a plan view of an ignition unit embodying the present invention, the distributor and distributor rotor being removed;

Fig. 3 is a wiring diagram showing in diagrammatic form the timer mechanism shown in Fig. 2, and also a diagrammatic representation of a distributor and of an induction coil, and electric connections between the several elements of the ignition unit;

Figs. 4 and 5 are diagrammatic plan views of the timer and distributor rotor of the ignition unit, showing relative position during normal and reverse rotation of the engine, respectively.

Referring to Fig. 2 of the drawings, 20 designates the ignition unit having a circular base 21, which is adapted to secure the unit in place upon the cam gearing housing of the engine, as shown in Fig. 1, which shows a multi-cylinder V-type engine having cam shafts placed above the cylinder heads. The usual end cover for the cam shaft gearing housing is replaced by the base 21, which serves as a support for a timer cup 24. The timer cup 24 is provided with bearings (not shown) for a central shaft 26, carrying at its upper end a timer cam 27 and distributor rotor 28.

The rotor 28 comprises an arm 34 of insulating material mounted on cam 27 and held 55 in proper relation with the cam by means of

locating pin 35, carried by the cam and engaging recess 35^a formed in the rotor. Both the rotor and cam are secured in place upon the shaft 26 by means of a screw 36^a, engaging in a tapped hole 36 in the end of the shaft 26. The cam 27 is broached as at 37 for the securing thereof upon shaft 26 in fixed relation. The rotor carries a metallic spring 38, which engages a rotary contact 39 of conducting material. The function of spring 38 will be described later.

41 designates a distributor track located above the timer cup and concentric therewith, in a manner which forms no part of the present invention, but which is described 70 in the co-pending application of William A. Chryst and John H. Hunt, Serial No. 208,369, filed December 22, 1917. Metallic stationary contact elements 43 are located upon the track, and are connected in proper 75 relation with the various spark plugs of the engine.

Upon the bottom of the timer cup 24 is mounted a breaker arm bracket 59, by means of pins 60, 61 and 62, extending through the 80 bracket and timer cup; and by means of a stud 63 mounted in the timer cup and having its upper end threaded to engage a nut 64. The pin 60 extends through a round hole in the bracket and serves as a pivot 85 about which the bracket may be swung for adjustment, which will be described later, slotted apertures being formed in the bracket for the reception of the pins 61 and 62, and for the stud 63.

It will be seen that by loosening the nut 64, the bracket 59 may be swung about the pin 60 to a desired position and may be secured by tightening the nut 64. The breaker arm bracket 59 carries breaker arms 65, 66 and 67, mounted upon posts 68 secured to the bracket, but insulated therefrom. The arms 65, 66 and 67 are provided with contacts 70, 71 and 72 respectively, which engage with stationary contacts 73, 74 100 and 75 respectively, which are adjustably mounted upon upturned ears 76, formed integral with the bracket 59. Springs 77, 78 and 79 are electrically connected at one end with the member 58 and at other portions 105 thereof with the arms 65, 66 and 67 respectively. The springs serve to keep the stationary and movable contacts in touching relation, except at such times when the cam co-operating with the fiber followers 80, 81 110

and 82 will cause the pairs of contacts to separate. Rubber cushions 83 are interposed between the ends of springs 77 and 78, and their respective arms, and serve to transmit the spring pressure to maintain the contacts in engagement. The rubber cushions 83 serve to absorb the shock, due to the sudden impact of the contacts when the cam permits the arms to swing back, and thus prevent rebound or chattering when revolving at high speeds. This feature, however, forms no part of the present invention, but is fully described and claimed in the patent of J. H. Hunt, No. 1,426,873, issued August 15, 1922.

A resistance coil 84, supported upon a spool 85 of nonconducting material, is interposed between the spring 79 and connecting plate 58, the purpose of which will be described later. The breaker arm bracket 59 is provided with an upturned projection 86, upon which is mounted a condenser casing 87, containing a condenser of well known construction shown diagrammatically in Fig. 3 at 88. One terminal of the condenser is connected with the connecting plate 58 by a wire 89, and the other terminal is grounded upon the bracket 59.

Referring to Fig. 3, 117 designates the primary winding, and 118 the secondary winding of the induction coil carried by a base 106 in any suitable manner. One end of the primary winding 117 is connected by wire 125 with binding post 125^a, carried by base 106. The other end of the primary 117 and one end of the secondary 118 are connected together by a wire 126, which is connected with binding post 127^a, by means of wire 127. The other end of secondary 118 is connected with a metallic button 129, carried by the base 106.

The circuits through the ignition unit are shown diagrammatically in Fig. 3, with a single source of current supply. The current from the battery 130, grounded on the motor base, passes through connections 54, 127^a, 127 and 126, through the primary winding 117, and connections 125, 125^a, and 54^a, to the connecting plate 58, from which are taken four parallel circuits. One circuit is formed through the breaker arm 65, contacts 70 and 73, to the distributor base which forms a ground connection on the engine; a second circuit is through resistance 84, breaker arm 67, contacts 72 and 75, to ground; a third circuit is through breaker arm 66, contacts 71 and 74, to ground; and the fourth circuit is through wire 89, condenser 88 to ground.

One end of the secondary circuit 118 is grounded through the battery or through the timer, and the other end may be connected with the rotor 28, as by button 129 contacting with spring 38. This connection is indicated diagrammatically by wire 129^a.

Attention is now directed to Figs. 4 and 5. The arrows in Fig. 4 indicate the direction of rotation of the cam and distributor rotor when the engine crank shaft is rotating in the normal direction. The arrows in Fig. 5 indicate the direction of rotation of these elements upon a reversal of the engine. Fig. 4 shows the relative position of the cam and cam followers just before the cam touches followers 80 and 81, and after engaging follower 82. It will be noted that upon rotation of the cam in the normal direction, contacts 72 and 75 will separate before contacts 70, 73 and contacts 74 and 71. Contacts 70, 73 and 74 and 71, are so located with respect to the cam that separation is effected simultaneously.

Adjustment to bring about this simultaneous separation is effected by means of the adjustable breaker arm bracket previously described. It will be seen that by rotating the bracket 59 about pin 60, the edges of cam followers 80 and 81 may be brought diametrically opposite to one another, so that both followers will be engaged by the cam lobes at the same time. This adjustment of followers 80 and 81 will not affect the relation of follower 82 to the cam, for the reason that follower 82 is the same distance from pin 60 as the center of cam 27. Hereafter breaker arms 65 and 66 with their parts co-operating therewith, will be known as main circuit breakers. The breaker arm 67 with its co-operating parts will be known as the resistance circuit breaker since resistance 84 is included between the breaker arm and the connecting plate 58. Two main circuit breakers are used so that in case of faulty adjustment of the breaker contacts, two chances are available of obtaining perfect contact during the period of closing of the primary circuit.

Upon reference to Fig. 5, it will be noted that upon a reversal of rotation of the cam, the main circuit breakers open before the resistance circuit breaker opens. Referring again to Fig. 4, it will be noted that just as the main circuit breakers open, the distributor rotor will be in contact with one of the stationary contacts 43, while, referring to Fig. 5, it will be seen that upon a reversal of the engine, the resistance circuit breaker will be closed when the main circuit breakers are open, with the result that all of the primary current must now pass through the resistance 84. When these conditions are present, the current in the primary will not only be greatly reduced, but the change in intensity of the magnetic field surrounding the induction windings will take place at a much slower rate than when the condenser only is in parallel with the main circuit breakers, with the result that the voltage induced in the secondary is greatly reduced so that no spark would jump at the 130

spark plug, were the greatly reduced sparking impulse to be distributed thereto.

As an extra precaution against sparking upon a reversal of the engine, the distributor rotor is so arranged with relation to the cam that at the time when the much enfeebled sparking impulse is induced in the secondary, the rotor will not be in contact with any one of the stationary contacts 43, but there will be a gap between these elements as shown in Fig. 5.

When the circuit is finally broken, upon the separation of the contacts of the resistance circuit breaker, the current in the primary has reached so low a value that there is very little tendency for a spark, and the presence of the charging resistance in the condenser circuit reduces the efficiency of the condenser in obtaining a sharp break of this small current, thereby aiding still further the elimination of a tendency for a spark. Thus a double protection against back-firing of the engine upon a reversal of rotation is afforded.

The timer is rendered ineffective to break the primary circuit in such a manner as to induce a current in the secondary of sufficient strength to cause sparking, and the distributor is rendered ineffective to distribute even the much weakened sparking impulse which may be created upon reversal of the engine. Therefore, the possibility of serious accidents and of damage to the engine, attendant upon back-firing, often occurring when the engine is started by rocking the propeller against compression, has been eliminated in a thoroughly reliable manner.

Fig. 1 shows an end view of a multi-cylinder engine 136, which is of the V-type, consisting of a crank case 137 upon which are mounted rows of cylinders 138 having their axes arranged at an angle of 45 degrees. 139 designates the crank shaft, and 140 and 141 designate the cam shafts, the overhead cam shafts operating valves (not shown), which control the inlet and exhaust ports of the cylinders. The cam shafts are driven from the crank shaft 139, by means of a gear 142, connected to the crank shaft, which drives the gear 143, mounted on a vertical shaft 144, which carries a gear 146.

A shaft 145 is connected with shaft 144 so as to drive a generator 135 for charging the battery 130, shown in Fig. 3. The battery charging circuit is disclosed in the co-pending application Serial No. 208,369, to which reference has been made.

Gear 146 meshes with gears 147 and 148, mounted on shafts 149 and 153 respectively, which are supported by pedestals 150 and 154 respectively. Shafts 149 and 153 carry at their upper ends gears 151 and 155, which mesh with gears 152 and 156, mounted upon the cam shafts 140 and 141 respectively. The relative size of the gears just described is

such that the cam shafts will rotate at one-half engine speed. Cam shafts 140 and 141 and the gearing co-operating therewith are inclosed in housings (not shown). Upon the ends of these housings are mounted ignition units 20^a and 20^b, the bases of which serve as covers for the housings.

The act of mounting the ignition units upon the cam shaft housings accomplishes the connection of the timer cam shafts 26 with cam shafts 140 and 141, and also accomplishes the making of an electrical connection between the ignition unit and the engine frame, upon which the source of ignition current supply is grounded. The timer arms 93 are connected together by means of rods 157 and 158, having threaded engagement with an intermediate turnbuckle 159. The rod 160 connected with the arm 93 of unit 20^a, is operably associated with any controlling lever within easy reach of the operator, by means of which the timer cups may be shifted about their respective axes, to effect advance or retard of the ignition. By adjusting the distance between the points of connection of rods 157 and 158, with arms 93, by means of turnbuckle 159, the time relation of the two units may be synchronized.

A high-tension conduit 163 mounted upon the intake manifold 164 serves as a housing for the high-tension cables leading from the distributor units 20^a and 20^b to the various spark plugs of the engine. Each engine cylinder is provided with two spark plugs so that in a 12-cylinder engine there will be two sets of spark plugs, twelve spark plugs in each set. One set of plugs is connected with the unit 20^a by means of the high tension cables 161, and the other set of spark plugs is connected with ignition unit 20^b by means of high-tension cables 162. In the embodiment of the invention disclosed there are in fact twelve, each of cables 161 and 162, but for the sake of clearness but two each of said cables 161 and 162 are shown.

It will be noted that the cam 27 is provided with asymmetrical lobes. The reason for this is that there may be provided a continuous series of sparking impulses of equal intensity, but in asymmetrical succession in order to provide ignition for the engine disclosed having asymmetrical firing order. This feature does not form a part of the present sole invention, but is described in detail and claimed in the co-pending application of William A. Chryst and John H. Hunt, Serial No. 208,369, filed December 22, 1917.

The distributor contacts 43 must also be asymmetrically spaced in correspondence with the timer cam lobes in order to distribute properly the sparking impulses to the various cylinders of an engine having asymmetrical firing order. By asymmetrical firing order, it is meant that the intervals be-

tween preceding and succeeding firing periods are not equal but are alternately equal. For example, in the case of a twelve cylinder engine having two rows of 6 cylinders in each row, and the axes of the two rows converging from the crank shaft at an angle of 45° degrees, the firing intervals are 45° degrees and 75° degrees of crank shaft rotation alternately. In the ignition timer which 10 operates at one-half engine speed, the spacing of the cam lobes and distributor contacts is 22½ degrees and 37½ degrees, alternately. This particular arrangement is substantially shown in the drawings.

15 While there has been shown but one condenser in the primary circuit of the ignition unit, it is understood to be within the province of this invention to provide a plurality of condensers in parallel, so that if any of 20 the condensers fail to operate, the remaining condensers will still be effective.

25 While the form of mechanism herein shown and described constitutes a preferred form of embodiment of the invention, it is 30 to be understood that other forms might be adopted, all coming within the scope of the claims which follow.

What I claim is as follows:

35 1. In an ignition system for internal-combustion engines, the combination with means for producing sparking impulses, which upon normal operation of the engine will provide ignition; of means operating upon reversal of the engine for weakening the 40 sparking impulses to a degree such that ignition will not be provided.

45 2. In an ignition system for internal combustion engines, the combination with means for producing sparking impulses, said means including an inductive winding and provisions, operable during normal engine rotation, for producing a relatively rapid change of magnetic flux in the region of said winding; of devices, operating during a reversal 50 of engine rotation, for effecting a relatively slow change of magnetic flux in the region of said winding.

55 3. In an ignition system for internal combustion engines, the combination with means for producing sparking impulses, said means including a secondary inductive winding, a current source, a primary inductive winding and provisions operable during normal engine rotation to obtain a relatively quick reduction of current in said primary winding; of devices, operating during a reversal of engine rotation, for effecting a relatively slow 60 reduction of current in said primary winding.

65 4. In an ignition system for internal combustion engines, the combination with a primary circuit for creating a magnetic field, and a secondary circuit in which is induced a current upon a change in the intensity of the field; of means for causing a decrease of flux

at a maximum rate during normal operation; and means operative upon a reversal of the engine for causing the decrease of flux to take place at a slower rate, whereby the voltage induced in the secondary is reduced 70 to a value less than that required to cause a spark in the engine cylinder.

5. In an ignition system for internal combustion engines, the combination with a primary circuit for creating a magnetic field 75 and a secondary circuit in which is induced a current upon a change in the intensity of the field; of means for causing a decrease of flux at a maximum rate during normal operation causing the induction of sparking impulses; means operative upon a reversal of the engine for causing the decrease of flux to take place at a slower rate, whereby the voltage induced in the secondary is reduced 80 to a value less than that required to cause a spark in the engine cylinder; and means for distributing sparking impulses to the engine cylinders upon normal operation of the engine, said distributing means being inoperative upon reversal of the engine to distribute 85 the weakened sparking impulse to any of the engine cylinders.

6. In an ignition system for internal-combustion engines, the combination with a current source and an ignition coil; of a timer 90 for controlling the delivery of current to said coil; and means effective upon a reversal of the engine for obtaining a comparatively slow dissipation of the energy of the coil whereby said timer will be ineffective to 95 cause said coil to provide ignition for said engine.

7. In an ignition system for internal-combustion engines, the combination with a current source and an ignition coil; of engine 100 controlled means controlling delivery of current to said coil for causing said coil to provide ignition during normal engine operation, but including provisions during a reversal of engine operation to produce a relatively slow dissipation of energy in said coil before the current in said coil is interrupted, whereby said coil cannot provide ignition for 110 the engine.

8. In an ignition system for internal-combustion engines, the combination of means for producing a series of sparking impulses in predetermined sequence bearing, during normal engine operation, a certain time relation to the engine cycle, but a different time of relation upon reversal of the engine; means for distributing to the various spark plugs in similar sequence during normal engine rotation, but inoperative to distribute 115 when the impulse producing means operates upon reversal of the engine; and means operative upon reversal of the engine to weaken the sparking impulses, whereby the tendency 120 of the distributor to function is gradually reduced.

9. In an ignition system for internal-combustion engines, the combination with a current source and an ignition coil; of a timer connected with the source and coil for effecting the creation of sparking impulses in a predetermined sequence bearing, during normal operation, a certain time relation to the engine cycle, but a different time relation upon reversal of the engine; a distributor arranged to distribute in similar sequence during normal operation, but ineffective to distribute when impulses are created during a reversal; and means operating during a reversal of engine operation to produce a relatively slow dissipation of energy in said coil before the current in said coil is interrupted by the timer, whereby said coil cannot provide ignition for the engine. 70 75
10. In an ignition system for internal-combustion engines, the combination with means for producing a series of sparking impulses in predetermined sequence bearing, during normal engine operation, a certain time relation to the engine cycle, but a different time relation upon reversal of the engine; means including a rotating contact and stationary contacts for distributing the sparking impulses to the various engine cylinders in similar sequence during normal engine rotation, but operating upon reversal in such a manner that, at the time when a sparking impulse would be created, a gap will exist between the distributor rotating contact and a stationary contact and means operative upon reversal of the engine to weaken a sparking impulse, whereby the tendency of the sparking impulses to jump said gap is greatly reduced. 80 85
11. In an ignition system for internal-combustion engines, the combination with primary and secondary circuits, a source of current in the primary circuit, and means for making and breaking the primary circuit during normal operation of the engine for creating sparking impulses in the secondary circuit; of means for rendering said primary circuit breaker ineffective to break the primary circuit during the reversal of the engine, at a time when a sparking impulse, if created, would be effective to ignite a charge of gas in the engine. 90 95 100 105
12. In an ignition system for internal-combustion engines, the combination with primary and secondary circuits, a source of current in the primary circuit, and means for breaking the primary circuit during normal operation of the engine for creating sparking impulses in the secondary circuit; of means operating upon reversal of the engine to place a shunt circuit around said primary circuit breaker at a time during reversal before the primary circuit breaker is opened. 110 115 120 125
13. In an ignition system for internal-combustion engines, the combination with primary and secondary circuits, a source of current in the primary circuit, and means for breaking the primary circuit during normal operation of the engine for creating 70 75 80 85 90 95 100 105 110 115 120 125 130 135 140 145 150 155 160 165 170 175 180 185 190 195 200 205 210 215 220 225 230 235 240 245 250 255 260 sistance circuit shunted around the main circuit breaker, including a breaker for the resistance circuit, said circuit breakers including stationary and movable contacts; an engine driven member having means for moving the movable contacts in timed relation to the engine, such that during the normal operation of the engine, the resistance circuit breaker will be in open position when the main circuit breaker opens, and so that during a reversal the resistance circuit will be closed at a time when the main circuit breaker opens; and a distributor in the secondary circuit, said engine driven member having provisions for operating the distributor in such a manner that during the normal operation of the engine, said distributor will function, and, during a reversal, will not function to distribute any sparking impulses which have been created.

18. In an ignition system for internal combustion engines, the combination of means for producing during normal operation a series of sparking impulses in a cycle bearing a certain time relation to the engine cycle; means for distributing the sparking impulses when produced in a similar cycle, the spark impulse producing means and distributor being so constructed that, upon a reversal of rotation of the engine, the distributor cannot function at a time when sparking impulses are produced; and means operative upon reversal to weaken the sparking impulses, whereby the tendency of the distributor to function is greatly reduced.

19. In an ignition system for internal combustion engines, the combination with primary and secondary circuits; of a timing device including cooperating contacts in the primary circuit; a distributing device in the secondary circuit; an engine driven member having means for opening the contacts to induce sparking impulses in the secondary circuit in recurrent sequence having a certain relation to the engine cycle during normal operation but a different relation during a reversal of the engine; means connected with the engine driven member for causing during normal operation the distribution of impulses in said recurrent sequence, but inoperative to distribute sparking impulses when created upon reversal of the engine; and means controlled by the engine driven member for weakening the sparking impulses upon a reversal, so that the tendency of the distributor to function is greatly reduced.

20. In an ignition system for internal combustion engines, the combination with primary and secondary circuits; of a timing device including cooperating contacts in the primary circuit; a distributing device including stationary contacts and a rotor contact in the secondary circuit; an engine driven mem-

ber having means for opening the contacts in the primary circuit at times having a certain relation to the engine cycle, during normal operation; means connected with the engine driven member for operating the rotor to distribute in a cycle similar to the timer cycle, the contact opening means operating upon a reversal of the engine in such a manner that a gap will exist between the rotor and any one of the stationary distributor contacts when the primary contacts are being opened; and means controlled by the engine driven member for weakening the sparking impulses caused by opening the primary contacts upon a reversal, so that the tendency of a sparking impulse to jump the aforesaid gap will be greatly reduced.

21. In an ignition system for internal combustion engines, the combination with primary and secondary circuits; of a timing device including cooperating contacts in the primary circuit; a distributing device including stationary contacts and a rotor contact in the secondary circuit; an engine driven member having means for opening the contacts in the primary circuit at times having a certain relation to the engine cycle, during normal operation; means connected with the engine driven member for operating the rotor to distribute in a cycle similar to the timer cycle, the contact opening means operating upon a reversal to change the time relation of the timer cycle to the distributor cycle, the change being so great that a gap will exist between the rotor and any one of the stationary distributor contacts when the primary contacts are being opened; and means controlled by the engine driven member for weakening the sparking impulses caused by opening the primary contacts upon a reversal, so that the tendency of a sparking impulse to jump the aforesaid gap will be greatly reduced, the means for weakening the sparking impulses consisting of a resistance and cooperating contacts in series and connected in parallel with the first mentioned contacts in the primary circuit, the engine driven contact opening means operating upon a reversal to open the first mentioned contacts at a time when the second mentioned contacts are closed, and during the normal operation to open the first mentioned contacts when the second mentioned contacts are in open position.

22. In an ignition system for internal combustion engines, the combination with a condenser unit in a circuit; of a resistance unit in a circuit parallel with the condenser circuit; means for periodically short circuiting both circuits; and means for periodically opening the resistance circuit.

23. In an ignition system for internal combustion engines, the combination with a condenser unit in a circuit; of a resistance unit

in a circuit parallel with the condenser circuit; means for periodically short-circuiting both circuits; and means for periodically opening the resistance circuit before the 5 end of each short-circuiting period during normal operation of the engine, said last named means operating upon a reversal of the engine for maintaining the resistance circuit closed at the end of each short-circuiting period.

24. In an ignition system for internal combustion engines, the combination with an inductive winding; of an engine operated member; means controlled thereby and effective during normal engine rotation for producing a relatively rapid change of magnetic flux in the region of said winding; and devices, controlled by said engine operated member, and effective during reversal of engine rotation to produce a relatively slow 15 20

change of magnetic flux in the region of said winding.

25. In an ignition system for internal combustion engines, the combination with a current source; of an ignition coil having primary and secondary windings; an engine driven member; means controlled thereby, and effective during normal engine rotation for producing a relatively rapid reduction of current in said primary winding; and devices controlled by said engine operated member, and effective during reversal of engine rotation to produce a relatively slow reduction of current in said primary winding. 25 30 35

In testimony whereof I affix my signature.
